(57) **CLAIM**

The ornamental design for a device mount, as shown and described.

DESCRIPTION

FIG. 1 shows a front perspective view of a device mount; FIG. 2 shows a front view of the device mount of FIG. 1; FIG. 3 shows a rear view of the device mount of FIG. 1; FIG. 4 shows a left side view of the device mount of FIG. 1; FIG. 5 shows a right side view of the device mount of FIG. 1; FIG. 6 shows a top view of the device mount of FIG. 1; and, FIG. 7 shows a bottom view of the device mount of FIG. 1. The broken lines depict portions of the device mount that form no part of the claimed design.

1 Claim, 7 Drawing Sheets
